DETACHABLE POURING SPOUT AND
CLOSURE FOR CONTAINERS

Arthur Read, Portland, Oreg., assignor, by mesne assignments, to "Pouring Spouts, Inc." Portland, Oreg., a corporation of Oregon

Application January 8, 1932, Serial No. 585,503
Renewed January 7, 1935

4 Claims. (Cl. 221—11)

My invention is intended for use in conjunction with containers within which materials may be stored and from which they may be poured, or disposed of at the will of the user.

5 My invention is primarily made of metal, fibre, paper, or any other suitable material, or a combination of all of them.

10 The invention primarily comprises a pouring spout attached to the container either during the process of manufacturing the container or at any other time thereafter. The spout may be removed from an empty container and applied to a new one of like or similar character.

15 An object of my invention consists in a method of attaching my device to the blank material from which the container is to be made so that it may be used to facilitate the filling of the container with the product to be presented to the market. Thereafter a sealing jacket is applied to thereby 20 seal my attachment to the container and to seal the opening formed therein in manufacturing or applying my device.

25 With these and incidental objects in view, the invention consists in certain novel features of construction and combination of parts, the essential elements of which are set forth in the appended claims, and a preferred form of embodiment of which is hereinafter shown with reference to the drawings which accompany and form 30 a part of this specification.

In the drawings:

Fig. 1 is a perspective, side view, of a container illustrating one of my new and improved pouring spouts disposed thereupon and in closed position.

35 Fig. 2 illustrates the container with one of my new pouring spouts in open position to receive a commercial product for subsequent delivery to the market.

40 Fig. 3 is a perspective, end view, of a container illustrating one of my new and improved pouring spouts associated therewith and in open position for use as a pouring spout.

45 Fig. 4 is a perspective, side view, of a container blank, and illustrating the same as being folded into position and illustrating a part of the same being cut out to form a pouring opening therein and in advance of my device being attached thereto.

50 Fig. 5 is a side view of a container having one of my devices attached thereto.

Fig. 6 is a plan view, of a blank from which the container is to be formed.

55 Fig. 7 is a perspective, corner view, of one of my new devices secured to the corner of a con-

tainer. In this view the pouring spout is shown in closed position.

Fig. 8 is a sectional, side view, of one of my new and improved pouring spouts in closed position. The view being taken on line 8—8 of Fig. 7, looking in the direction indicated. 5

Fig. 9 is a perspective, side view, of my device removed from a container.

Fig. 10 is a perspective, plan view, of my device in open position. 10

Fig. 11 is an inverted, perspective, plan view, of the pouring spout illustrated in Fig. 10.

Fig. 12 is a sectional, side view, of the pouring spout as illustrated in Fig. 7, the same being taken on line 12—12 of Fig. 7, looking in the direction 15 indicated.

Fig. 13 is a fragmentary, sectional, side view of the pouring spout, illustrating a locking lip in clamping position when upon the container to which the same is attached. 20

Like reference characters refer to like parts throughout the several views.

My device is primarily adapted for being placed upon containers in which granulated, or other products are to be stored and from which the 25 same are to be poured in portions, as required.

The device is adapted for being placed upon the container either during the process of its manufacture, or for being attached to the container at the point of use of the container. If 30 the device is to be attached to the container during the process of its manufacture, the same would be made as illustrated in Figs. 2, 4, 5 and 6.

The blank from which the container is to be made is illustrated at 1 and a cut-out portion 2 35 is formed within the blank that creates an opening 3 within the container when the blank of the container has been folded. When so made the body element 4 may be attached thereto and the container 5 be then filled by the placing of 40 the same under the hopper 6, the lower end of which is placed in registry with the opening 3 and the container is filled with the materials to the full capacity of the container. Thereafter the spout is hinged down as illustrated in Fig. 1 45 and the cover jacket 7 is then placed upon the container.

The pouring spout comprises a body element that is formed of a top 8 and side walls 9 and 10. The top portion 8 is cut out, as illustrated at 11, 50 sufficiently to form an opening through the top, that is adapted for being placed in registry with the opening 3 formed at the corner of the container. Locking tongues 12 are punched from the respective side walls and are forced inwardly 55

sufficiently to cause the same to grasp the side walls of the container and to be held firmly thereto. Locking tongues 13 are formed from the side wall 10. Openings are formed within the side wall 9 through which the locking tongues may be made to pass, thereafter the locking tongues are bent over sufficiently to secure the side walls 9 and 10 rigidly together.

A locking flange 14 is formed from the side wall 9 to further stiffen the assembly. The pouring spout is formed by a side wall 15 and a closure plate 16, both of which are united along their abutting edges, and hinged to the top member 8 by any suitable means as through the use of hinge pin 17. A slit 18 is formed within the top 8 and the outer peripheral edge of the side wall 15 is adapted for engaging the arcuate rim 19 of the side wall 15, the purpose and object of which are to maintain the side wall 15 in intimate engagement with the edge 20 of the top member 8.

A ledge 21 is formed at the meeting edges of the side walls 15 and 16 and the same is adapted to rest upon and engage the top 22 of the body element and to prevent the spout from being overforced into the opening 11. A lifting lip 23 is formed integral with the side wall 16 to facilitate opening the same.

Where my device is to be removably secured to the container and is to be placed upon other containers the same may be made as illustrated in Figs. 8 to 12 inclusive, and when so formed locking spring ears 24 and 25 of curved formation are formed from the body element and bent up to and made to engage the inner surfaces 26 and 27 of the side walls 9 and 10 for gripping engagement with the walls of a container. Locking tongues 28 and 29 are formed in the locking ears 24 and 25.

The locking ears may be made as illustrated in Fig. 13 and when so made a lug 30 is formed integral with, and outwardly extends from both walls 15 and 16.

An offset 32 is formed integral with the locking ears 28 and 29 and the offset is placed in registry with the lug 30 so that as the pouring spout is fully closed the lug passes the offset with a spring action to maintain the spout in full lowered and locked position. A stop 33 is provided within the base of the pouring spout that prevents the disengagement of the spout with the slit 18.

While I have described and illustrated the container having one of my new and improved devices secured thereto at the point of filling of the container and having illustrated the container as having been filled through the open pouring spout, the carton may be filled with equal facility by the closing of the pouring spout and the filling of the container through the top of the container before the top is put into position.

While the form of mechanism and the method herein shown and described are admirably adapted to fulfill the objects primarily stated, it is to be understood that it is not intended to confine the invention to the one form of embodiment and the one method herein shown and described as it is susceptible of embodiment in various forms, and in methods all coming within the scope of the claims which follow.

What I claim is:

1. In a device of the class described, the combination of a body element comprising side walls and a top interconnected along their edges, a pouring opening formed through the top, the body element being formed of a single piece of flat material, a V-shaped pouring spout formed of two angularly disposed interconnected walls, one of said walls being hingedly connected along one of its edges adjacent the pouring opening, the other of said walls adapted to move freely in and out of said opening upon upward or downward movement of the said hinged wall in opening or closing said pouring opening.

2. In a device of the class described, the combination of a body element comprising side walls and a top interconnected along their edges, a pouring opening formed through the top, the body element being formed of a single piece of flat material, a V-shaped pouring spout formed of two angularly disposed interconnected walls, one of said walls being hingedly connected along one of its edges adjacent the pouring opening, the other of said walls adapted to move freely in and out of said opening upon upward or downward movement of the said hinged wall in opening or closing said pouring opening, limit stops formed integral with both walls of said spout for limiting opening and closing movement of said spout.

3. In a device of the class described, the combination of a body element formed of vertical side walls and a horizontal top adapted to engage the corner of a container, a pouring opening formed through the top of the body element in alignment with an opening formed in the corner of the container, a pouring spout comprising a pair of angularly disposed walls united along their edges and hingedly mounted to the horizontal top adjacent the opening therein by means of a hinge formed at one edge of said walls, limit stops formed integral with both walls of said pouring spout to limit opening and closing movement of the same, one wall of said spout adapted to form a closure for said pouring opening when the spout is in closed position, and means formed within said vertical walls of the body element for removable engagement with said container.

4. In a device of the class described, the combination of a body element formed of vertical side walls and a horizontal top adapted to engage the corner of a cardboard container, a pouring opening formed through the top of the body element in alignment with an opening formed in the corner of the cardboard container, a pouring spout comprising a pair of angularly disposed walls united along their edges and hingedly mounted to the horizontal top adjacent the opening therein by means of a hinge formed at one edge of said walls, limit stops formed integral with both walls of said pouring spout to limit opening and closing movement of the same, one wall of said spout adapted to form a closure for said pouring opening when the spout is in closed position, and means formed within said vertical walls of the body element for removable engagement with said cardboard container, said means comprising a plurality of locking tongues formed integral with the side walls of the body element and inclined inwardly toward the walls of the carton.

ARTHUR READ. 70
